FIG. 2.

Inventor:
Louis C. Loewenstein,
by *Alfred J. Davis*
His Attorney.

UNITED STATES PATENT OFFICE.

LOUIS C. LOEWEINSTEIN, OF LYNN, MASSACHUSETTS, ASSIGNOR TO GENERAL ELECTRIC COMPANY, A CORPORATION OF NEW YORK.

CENTRIFUGAL COMPRESSOR.

1,262,527.

Specification of Letters Patent. Patented Apr. 9, 1918.

Application filed June 30, 1916. Serial No. 106,923.

To all whom it may concern:

Be it known that I, LOUIS C. LOEWEINSTEIN, a citizen of the United States, residing at Lynn, in the county of Essex, State 5 of Massachusetts, have invented certain new and useful Improvements in Centrifugal Compressors, of which the following is a specification.

The present invention relates to centrifugal compressors and to the governing mechanism therefor.

In many instances it is necessary to vary both the quantity and the pressure of air delivered by a compressor over wide ranges, 15 especially in connection with converters used in the process of smelting metals. For example, in one instance with which I am familiar, the quantity of air required at the start is 2500 cubic feet of free air per minute, which quantity is gradually increased in the course of substantially a two-hour run to 25,000 cubic feet of free air per minute, the pressure in the meanwhile also increasing.

25 The variation of quantity and pressure can readily be obtained when the compressor is driven by an elastic fluid turbine because the latter is capable of being driven at widely varying speeds without having its economy seriously impaired. On the other hand when the compressor is driven by an alternating current motor of the asynchronous type, for example, it is only possible to vary the speed over wide ranges at a great sacrifice in economy of operation. Roughly, it takes as much current to operate such a motor at very low speeds as it does to operate it at full speed. This is due to the fact that current consuming or wasteful resistance has to be included in the motor circuit, and the lower the desired speed the greater will be the amount of resistance used with its corresponding loss of energy. It is possible, however, to obtain some variations in speed without excessive losses due to resistance. For example, a variation of speed from 1100 R. P. M. to 1400 R. P. M. is within good engineering practice.

30 The object of my invention is to so organize and construct the compressor, its driving motor, and governing mechanism, that the output of the compressor can be varied from minimum to maximum without undue waste of energy.

35 To accomplish this a multi-stage compressor

is provided which has a number of outlet conduits opening into the supply main leading to the point of consumption instead of a single outlet conduit, as is the common practice. In each conduit is a valve for cutting it into and out of service, it being understood that only a single conduit is in service at a time. These valves may be operated by hand or by motors as desired. When motor operated, they may be controlled from a distance, for example, at the place where the air is used instead of at the compressor, which is generally remote from the point of consumption.

36 As before stated, an asynchronous alternating current motor is capable of limited speed variation. I, therefore, connect the first outlet conduit to the compressor at such a point that it will deliver the desired quantity of air for one portion of the cycle of 75 operation, while the speed of the motor is changing from its minimum to its maximum. A second outlet is connected to the compressor at such a point that it will deliver with the minimum speed of the motor substantially the same quantity and pressure of air as was previously delivered by the first outlet at maximum speed of the motor. A third outlet is or may be provided which, with the minimum speed of the motor, 80 delivers substantially the same amount of air that the second did with maximum speed of the motor. These conduits may be duplicated at will. To state the matter in another way, a step-by-step operation is provided in which the motor operates at its predetermined minimum speed at the start and is then increased to its predetermined maximum speed. A change is then made in the compressor outlet connections and the 85 cycle of operation of the motor is repeated.

40 If each stage of the compressor is arranged to deliver air with substantially the same added increment of pressure, the outlet conduits will not be connected to the successive stages. For example, in an eight stage machine, the second, third, fifth, and eighth stages may be provided with these outlet conduits. On the other hand, if the impeller diameters enlarge from the inlet to 105 the final stage in such manner that the added increment of pressure is sufficiently greater stage by stage, then each stage may be provided with an outlet conduit.

45 The compressor is also provided with a 110

governing mechanism which is acted upon by the air passing through it. A suitable mechanism for the purpose is found in the patent to Richard H. Rice No. 919,953 dated April 27, 1909. This mechanism includes a float located in the inlet which is connected by a rod to a tilting beam on which is mounted a weight that balances the float and permits it to assume definite positions in the inlet, depending upon the amount of air flowing through the compressor. To obtain the wide variation in quantity required in this case, I modify said mechanism by mounting a lead screw longitudinally of the beam and continuously or intermittently rotate it at a low rate of speed through suitable gearing from an electric or other motor. The weight is moved by the lead screw along the beam. If the total cycle takes two hours to complete, then the lead screw will take that time to move the weight from its initial to its final position. For any given quantity of air flowing the weight will have a corresponding position on the beam.

To control the speed of the compressor driving motor, a water or other rheostat is provided in its circuit, the movable member or members of which are adjusted by the beam as it moves in response to the action of the float.

Assuming a cycle of operation of a converter as referred to above with a minimum quantity of air required at the start, the outlet conduit leading from the second stage will be opened to the supply main and the others will be closed. The position of the weight on the beam will, when the circuit is closed, cause the motor 30 to start at or near its minimum speed with all or nearly all resistance in circuit. As the weight is moved by its motor along the beam the speed of the driving motor and the compressor will gradually increase to or near to the maximum due to the cutting out of resistance. The operating engineer noting this fact from the position of the beam, or by reason of a signal operated by the beam, opens the valve in the second outlet conduit and closes the first. This can also be done automatically by obvious means. The inclusion of these additional stages is, for the existing position of the weight on the beam, sufficient to supply the desired quantity of air at the requisite pressure at or near the minimum speed of the driving motor, whereas the motor when the second outlet was opened was operating at or near its maximum speed. As a result of this there will be a rush of air through the compressor in excess of that which the weight indicates, and the float will immediately change its position cutting in full resistance in the motor circuit, thus reducing the motor speed to its minimum, and the air flow to that for which the governor weight is set. The slow but continuous

movement of the weight due to its motor and lead screw permits the float to gradually change its position and cut resistance out of the motor circuit until the speed of the motor is at its maximum, when the third outlet conduit is opened and the second closed and the cycle of operation is again repeated.

In the accompanying drawing which is illustrative of my invention, Figure 1 is a diagrammatic view of a multi-stage air compressor supplying compressed air to a converter; and Fig. 2 is a diagram illustrating the cycle of operation.

5 indicates a multi-stage centrifugal air compressor of any suitable construction. Communicating with the second, third, fifth, eighth and last stages thereof are outlet conduits 6, 7, 8, 9 and 10, said conduits discharging into the supply main or header 11 that conveys air to the pivotally supported converter 12. In each of said outlet conduits is a valve 13 which is opened and closed by an electric motor 14, through suitable gearing, or the valves may be actuated manually if desired. In the header 11 is a suitably operated balanced valve 15, by means of which the air supply to the converter can be quickly interrupted, if occasion arises. The converter is mounted on 95 two diametrically opposite trunnions 16, by means of which it can be tilted by the motor 17 and worm gearing 18 to discharge the contents thereof.

19 is a float mounted in the conical end 100 of the intake pipe 20. The float is attached by a rod 21 to the pivoted beam 22. 23 is a dash-pot to prevent too sudden movements of the beam. Mounted to slide on the beam is a balancing weight 24 which is moved from its neutral to its final position by the lead screw 25 driven by the electric or other motor 26. The armature of the motor is connected to the screw through speed reducing worm gearing 27, the arrangement being 110 such that the weight will complete its movement during the predetermined cycle of operation of the converter.

Pivoted connected to the right-hand end of beam 22 is one end of a lever 22^a fulcrumed to 22^b. The other end of lever 22^a is connected by a rod 28 to the regulator. As shown it comprises a three-phase water rheostat having adjustable plates 29 whereby the speed of the driving motor 30 may 120 be varied between the predetermined limits. This is a well known means for the purpose.

Fig. 2 illustrates diagrammatically the cycle of operation. Initially the second stage valve 13 is opened and the others are 125 closed. The motor 20 is then started and operated at low speed for say ten minutes. The motor 26 is then started, which causes the weight 24 to move toward the left-hand end of the beam, with the result of gradu-

ally decreasing the resistance in the motor circuit, and gradually increasing the motor speed. When the speed has reached the maximum, say 1400 R. P. M., the valve in outlet conduit 7 is opened and that in 6 closed. At the time this change is made the rheostat plates are quite close together and the speed of the compressor and its motor is substantially at the maximum. This change of outlet will by reason of the increased quantity of air delivered cause the float 19 to assume a new and higher position, and cut resistance into the motor circuit, thereby quickly decreasing its speed until the quantity of air and pressure delivered through outlet conduit 7 corresponds at the reduced speed to substantially the same quantity and pressure of air which was formerly delivered by the outlet conduit 6 at maximum speed of the motor. As the motor 26 continues to rotate the lead screw, the weight 24 will gradually increase the speed of the driving motor 30 to the maximum when outlet conduit 8 is opened and conduit 7 closed, and the operation repeated as above described. From Fig. 2 will be seen in what portions of the complete cycle the different discharge outlets are in service. From this figure it will also be seen that the quantity and pressure of the air delivered to the converter varies during the two and a half hour run from 2500 cubic feet of free air per minute to 25,000 cubic feet of free air per minute. The pressure varies from about two lbs. per square inch to fifteen. For any desired period of time after the last outlet conduit is opened the compressor may operate at its full capacity, as indicated. These figures, it is to be understood, are given as illustrations and not as limitations of my invention, since the cycle of operation can be modified to meet any desired condition. If it be desired to change the rate of movement of the weight 24 more or less resistance may be included in the circuit of the motor 26, as is usual in such cases, and the motor can be temporarily stopped if desired by opening the switch 31. At the end of the cycle the weight 24 can be disconnected from the lead screw and moved back by hand or in any other suitable manner.

As the compressor will generally be located in the power house and the valves 13 in the converter house, a signal may be provided, such as an incandescent lamp or bell 32 located in the converter house, to warn the operator that the maximum speed of the driving motor for a given portion of the cycle has been reached, and that another discharge outlet should be opened. This may be done by having the weight carrying beam close the lamp or bell circuit by contacts 33 when it reaches its extreme position. The valves 13 may, however, be lo-

cated in the power house which means a reduction in the amount of piping required.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The method of operating a multi-stage compressor which is driven by a motor having a limited range of economical speed, which consists in including a predetermined number of stages in service, increasing the speed of the motor from a predetermined low to a predetermined higher speed, cutting additional stages into service and reducing the speed of the motor, and thereafter increasing the speed of the motor to said higher speed.

2. In combination, a multi-stage centrifugal compressor arranged to operate from no-load to full capacity, a driving motor therefor which has a limited range of operating speed, means for varying the number of stages of the compressor in operation, and governing mechanism for varying the speed of the driving motor from a predetermined low to a predetermined higher speed for each setting of said means.

3. In combination, a multi-stage centrifugal compressor arranged to operate from no-load to full capacity, a driving motor therefor which has a limited range of operating speed, valve controlled conduits leading from different stages of the compressor to the point of consumption, and governing mechanism responsive to the flow of fluid through the compressor for increasing the speed of the driving motor from its predetermined minimum to its predetermined maximum each time one of said conduits is opened.

4. In combination, a multi-stage centrifugal compressor having discharge outlets leading from various determined stages which are so arranged that each succeeding outlet after the first will, at reduced speed of the driving motor, deliver substantially the same quantity and pressure of fluid as was delivered by the preceding outlet with a greater speed of the driving motor, a driving motor whose speed may be varied between certain limits, and means for varying the speed of the motor.

5. In combination, a multi-stage centrifugal compressor having discharge outlets leading from various determined stages which are so arranged that each succeeding outlet after the first will, at the predetermined minimum speed of the driving motor,

- deliver substantially the same quantity and pressure of fluid as was delivered by the preceding outlet at the predetermined maximum speed of the driving motor, means for 5 opening and closing said outlets, a driving motor whose speed may be varied between certain minimum and maximum limits of speed, and means for automatically varying the speed of the motor between said limits 10 during the period that each of said outlets is in service.
6. In combination, a multi-stage centrifugal compressor, a motor for driving it, valve controlled conduits leading from different stages of the compressor to the point of consumption, a regulator for the motor, a float responsive to changes in the rate of flow of fluid through the compressor, a beam attached thereto, a weight arranged to be 15 moved along the beam a predetermined distance for each conduit as it is opened to vary the speed of the motor, and means actuated by the beam for moving the regulator.
7. In combination, a multi-stage centrifugal compressor, a motor for driving it, valve controlled conduits leading from different stages of the compressor to the point of consumption which are cut into service successively, a regulator for the motor, a 20 governing mechanism which is responsive to a condition of the fluid flowing through the compressor, a connection for transmitting motion from said mechanism to the regulator, and a means actuated by a separate source of power which progressively changes 25
- the effective action of the governing mechanism during the cycle of operation of the compressor.
8. In combination, a multi-stage centrifugal compressor, a motor for driving it, 40 conduits leading from different stages of the compressor to the point of consumption, valves to cut them into and out of service, a regulator for the motor, governing mechanism responsive to changes in a condition 45 of the fluid flowing through the compressor, a regulator for the motor which is actuated by said mechanism, and a means separately actuated for causing said mechanism to move the regulator in a manner to progressively increase the speed of the motor to a predetermined maximum during the period that each of said conduits is delivering fluid.
9. In combination, a multi-stage centrifugal compressor, a motor for driving it, 50 valve controlled conduits leading from determined stages of the compressor to the point of consumption, a regulator for the motor, a governing mechanism for the compressor which tends to cause the same to deliver a constant quantity of fluid, and a means actuated by a separate source of power which progressively loads said mechanism in such manner as to cause it to progressively increase the quantity of fluid delivered by the compressor.
- 55
- In witness whereof, I have hereunto set my hand this 27th day of June, 1916.
- LOUIS C. LOEWENSTEIN.
